(57) **CLAIM**

The ornamental design for a push pole anchor bracket, as shown and described.

DESCRIPTION

FIG. 1 is a perspective view of a push pole anchor bracket, particularly for mounting on a side surface of a marine vessel;

FIG. 2 is a front elevation view thereof;

FIG. 3 is a rear elevation view thereof;

FIG. 4 is a top view thereof; and,

FIG. 5 is a side view thereof.
